US0D1068650S

(12) **United States Design Patent** (10) **Patent No.:** **US D1,068,650 S**
(45) **Date of Patent:** **** Apr. 1, 2025**

(54) **CHARGER FOR ELECTRIC VEHICLE**

(71) Applicant: **LG ELECTRONICS INC.**, Seoul
(KR)

(72) Inventors: **Sangwon Yoon**, Seoul (KR); **Hongseok Kim**, Seoul (KR); **Seungdon Lee**, Seoul (KR)

(73) Assignee: **LG ELECTRONICS INC.**, Seoul
(KR)

(**) Term: **15 Years**

(21) Appl. No.: **29/894,071**

(22) Filed: **Jun. 6, 2023**

(30) **Foreign Application Priority Data**

Jan. 5, 2023 (KR) 30-2023-0000554

(57) **CLAIM**

The ornamental design for a charger for electric vehicle as shown and described.

DESCRIPTION

FIG. 1. is a front perspective view of a charger for electric vehicle showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the charger for electric vehicle that form no part of the claimed design.

1 Claim, 7 Drawing Sheets
